UNITED STATES PATENT OFFICE.

FRANK D. PELTIER, OF MOUNT CLEMENS, MICHIGAN.

DESIGN FOR A CARD-HOLDER.

45,817.

Specification for Design.

Patented May 19, 1914.

Application filed March 26, 1914. Serial No. 827,496. Term of patent 14 years.

To all whom it may concern:

Be it known that I, FRANK D. PELTIER, a citizen of the United States of America, residing at Mount Clemens, in the county of Macomb and State of Michigan, have invented a new, original, and ornamental Design for a Card-Holder, of which the following is a specification, reference being had to the accompanying drawing, forming part thereof.

I claim:

The ornamental design for a card holder, as shown.

FRANK D. PELTIER.
